Primary Examiner — Amy C Wierenga*Assistant Examiner* — Andrea Marie McKay(74) *Attorney, Agent, or Firm* — IPro, PLLC(57) **CLAIM**

The ornamental design for a mattress pad heater, as shown and described.

DESCRIPTION

FIG. 1 is a perspective view of a mattress pad heater showing the new design;

FIG. 2 is a perspective view viewed from another angle thereof;

FIG. 3 is a front elevation view thereof;

FIG. 4 is a rear elevation view thereof;

FIG. 5 is a left side elevation view thereof;

FIG. 6 is a right side elevation view thereof;

FIG. 7 is a top plan view thereof; and,

FIG. 8 is a bottom plan view thereof.

The broken lines in the figures illustrate portions of the mattress pad heater that form no part of the claimed design.

1 Claim, 8 Drawing Sheets(56)
